UNITED STATES PATENT OFFICE.

WALTER KLINE, OF MOGADORE, OHIO.

DESIGN FOR A TIRE-TREAD.

55,425.

Specification for Design.

Patented June 8, 1920.

Application filed February 3, 1920. Serial No. 355,980. Term of patent 7 years.

To all whom it may concern:

Be it known that I, WALTER KLINE, a citizen of the United States, and resident of Mogadore, in the county of Summit and State of Ohio, have invented a new, original, and ornamental Design for Tire-Treads, of which the following is a specification, reference being had to the accompanying drawing, forming part thereof.

The drawing shows a pneumatic tire casting in perspective, only a portion of the tread being shown in full and embodying the new design.

I claim:

The ornamental design for a tire tread, as shown.

WALTER KLINE.
